DESIGN FOR A TRIGGER GUARD FOR FIREARMS

Iver O. Mossberg, West Haven, Conn., assignor to O. F. Mossberg & Sons, Inc., New Haven, Conn.,
a corporation of Connecticut

Application March 9, 1938, Serial No. 75,707

Term of patent 7 years

To all whom it may concern:

Be it known that I, Iver O. Mossberg, a citizen of the United States, residing in West Haven, in the county of New Haven and State of Connecticut, have invented a new, original, and ornamental Design for a Trigger Guard for Firearms, of which the following is a specification when taken in connection with the accompanying drawing, in which

I claim:

The ornamental design for a trigger guard for firearms substantially as shown.

IVER O. MOSSBERG.
